UNITED STATES PATENT OFFICE.

GEORGE CROSSLAND, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

POSITIVE SHUTTLE-MOTION FOR LOOMS.

1,268,098.

Specification of Letters Patent. Patented June 4, 1918.

Application filed March 20, 1917. Serial No. 156,178.

To all whom it may concern:

Be it known that I, GEORGE CROSSLAND, a citizen of the United States, residing at Worcester, in the county of Worcester and State of Massachusetts, have invented a new and useful Positive Shuttle-Motion for Looms, of which the following is a specification.

This invention relates to a positive shuttle motion for looms of the type in which the shuttle is passed through the shed by reciprocating rods detachably and alternately engaging the shuttle.

In such looms, the shuttle is commonly pushed to the center of the loom by a reciprocating rod which engages the rear end of the shuttle and it is thereafter drawn along the remaining portion of its flight by a second reciprocating rod which engages the front end of the shuttle.

It is the object of my invention to provide improved mechanism for reciprocating the said rods and particularly for giving the rods a variable speed motion gradually decreasing in velocity as the shuttle approaches the boxes and as it approaches the center point of its flight.

In its preferred form this mechanism comprises a crank shaft having oppositely disposed crank pins and connections from said crank pins to the reciprocating rods. I have herein shown the invention as applied to a loom using two shuttles, but it will be apparent that the invention is equally applicable to a loom using a single shuttle.

A further feature of my invention relates to means for alternately disengaging the reciprocating rods from the shuttles in a double shed loom.

My invention further relates to certain arrangements and combinations of parts which will be hereinafter described and more particularly pointed out in the appended claims.

A preferred form of my invention is shown in the drawings, in which—

Figure 1 is a front elevation of my improved shuttle motion;

Fig. 2 is a left-hand side elevation partly in section, taken along the line 2—2 in Fig. 1, with certain parts omitted for the sake of clearness;

Figs. 3 and 4 are a front elevation and plan view respectively of one of the devices

for attaching the reciprocating rods to the shuttle;

Fig. 5 is an enlarged front elevation of a portion of the shuttle motion, and

Fig. 6 is a plan view of the parts shown in Fig. 5.

Referring to Fig. 1, I have shown therein my invention as embodied in a double shuttle loom. In this figure the upper shuttle boxes are indicated at 10 and 11 and the lower boxes at 12 and 13. The lay and the operating mechanism therefor is omitted for the sake of clearness. The reciprocating rods by which the shuttles are actuated are shown at 14, 15, 16, and 17. The rods 14 and 15 are clamped in a carrier 18 which is mounted to slide in fixed ways 19 (Fig. 2) mounted on the frame of the loom. The rods 16 and 17 are similarly secured in a carrier 20 slidable in ways on the right-hand side of the loom.

The carriers 18 and 20 are connected by links 21 and 22 to levers 23 and 24 mounted to swing respectively about fixed pivots 25 and 26. The levers 23 and 24 are connected by links 27 and 28 to oppositely disposed crank pins 29 and 30 (Fig. 5), carried by a crank shaft 31 rotatable in fixed bearings 32 and 33 (Fig. 6). The crank shaft 31 is intermittently rotated by dwell gearing comprising a mutilated pinion 34 fixed to the shaft 31 and a mutilated gear 35 (Fig. 5) loosely mounted on a driven shaft 36.

Provision is made for securing the gear 35 to the shaft 36 in any desired angular relation thereto, and for this purpose a toothed disk 37 is keyed to the shaft 36, and a notched plate 38 is detachably secured to the gear 35. The plate 38 fits between lugs or projections formed on the web of the gear 35, and when the plate 38 is in position between said projections the angular relation of the gear 35 and the plate 38 cannot be changed. If it is desired to change this relation the plate 38 is removed and is replaced after the angular relation of the parts has been adjusted.

Bolts or screws 39 threaded into the gear 35 and extending through slots in the toothed disk 37 provide means for firmly securing the gear 35 to the disk 37 and shaft 36, which latter is continuously rotated from any convenient driving member.

In Figs. 3 and 4, I have shown one form of mechanism for attaching the reciprocating rods 14, 15, 16 and 17 to the shuttles. I have selected for illustration the attaching mechanism M for the rod 14 and on Fig. 1 5 I have indicated by brackets the location of the attaching mechanism M', M², and M³ for the rods 15, 16 and 17 respectively.

The mechanism M comprises a head 40 10 formed on or secured to the rod 14 and having a lip or wing 41 projecting at an angle from the forward end thereof. The end of the head 40 is recessed at 42 to receive a notched projection 43 formed on the end of the shuttle. A locking lever 44 is pivoted at 45 on the head 40, and a spring 46 forces the lever into locking position, in which position a lug 47 formed on the lever extends through an opening 48 in the side of the 15 head 40 and locks the projecting member 43 into the recess 42.

A releasing lever 50 is pivoted at 51 upon the head 40 and one portion of the lever engages the rear end 44^a of the locking lever 20 25 44. The opposite end of the lever 50 supports a plate 52 in position for engagement by the end of a releasing rod 53 (Figs. 2 and 4). When thus engaged, the lever 50 will move upon its pivot, carrying with it 30 the lever 44 and withdrawing the projection 47 from the slot in the projecting member 43, thus releasing the shuttle.

I will now describe the mechanism for actuating the releasing rod 53. Referring to 35 Fig. 2, the releasing rod 53 which co-operates with the reciprocating rod 14 and a similar rod 54 which co-operates with the reciprocating rod 15 are connected to opposite arms of a three-armed lever 55 mounted upon a 40 fixed pivot 56. The rods 53 and 54 are slidable in fixed bearings 57 and 58 into and out of the path of movement of the releasing plates 52 carried by the reciprocating rods 14 and 15. The third arm of the lever 45 55 is connected by a link 60 to a lever 61 mounted on a shaft 62 which is connected by an arm 620 and a link 63 to a lever 64 mounted on a fixed pivot 65, and provided with a cam follower 66 through which the 50 lever 64 is moved by a face cam 67. This cam is continuously rotated in any convenient way, and is provided with a concentric portion 67^a which temporarily retains the rod 53 in operative position, and 55 with a corresponding concentric portion 67^b which retains the rod 54 in operative position.

Similar rods 70 and 71 are provided for 60 releasing the shuttles on the right-hand side of the loom, and the shaft 62 is extended across the loom and provided with a second arm 72 connected by a link 73 to actuate the rods 70 and 71.

Having described the details of construction of my improved mechanism, I will

briefly describe the operation thereof. Upon the rotation of the crank shaft 31 the levers 23 and 24 will be drawn toward each other, simultaneously advancing the carriers 18 and 20, and the reciprocating rods mounted 70 therein. Assuming that shuttles are positioned in the boxes 10 and 13, the rods 14 and 17 will be connected thereto by their locking levers 44 and as the rods are advancing the shuttles will be pushed to their 75 central positions. As they reach this point the releasing plates 52 will be engaged by the releasing rods 53 and 71, and at the same time the attaching heads of the rods 15 and 16 will engage the projections on the 80 forward ends of the shuttle, and will be locked thereto. During this operation the crank shaft will have made one half of a revolution.

During the second half of the revolution 85 the levers 23 and 24 will be drawn apart, reciprocating the carriers 18 and 20 in the opposite direction, and thus drawing the shuttles out of the shed and into the opposite shuttle boxes. The cam 67 will then 90 shift the three-arm lever 55, withdrawing the releasing rods 53 and 71 and advancing the rods 54 and 70 into position to release the shuttles at the center of their next succeeding flight.

The dwell gearing between the driven shaft 36 and the crank shaft 31 permits the shuttles to remain in the shuttle boxes during the beating up of the filling, and the crank motion brings the shuttles to a complete stop both in the shuttle boxes and also in the center of their flight. If it is necessary to change the timing of the shuttle flight with relation to the other parts of the loom mechanism, this change can be 105 made by adjusting the gear 35 upon the shaft 36, using the adjusting mechanism shown in Fig. 5 and previously described.

Having thus described my invention, it will be evident that changes and modifications can be made therein by those skilled in the art without departing from the spirit and scope of my invention as set forth in the claims, and I do not wish to be otherwise limited to the details herein disclosed, 110 but what I claim is—

1. A positive shuttle motion for looms comprising rods mounted at opposite sides of the loom and adapted to be alternately connected to the shuttle, and means to reciprocate said rods simultaneously in opposite directions, said means comprising a driven shaft, a mutilated gear loose on said shaft, a pinion intermittently rotatable by said gear, crank pins rotatable by said pinion, connections from said pin to said rods, and means to secure said mutilated gear to said driven shaft in adjusted angular position, said means comprising a toothed disk tight on said shaft, a notched plate detachably 125 130

secured in fixed position on said gear and effective to engage any desired portion of said toothed disk, and means to clamp said gear to said disk.

- 5 2. A positive shuttle motion for looms comprising rods mounted in pairs at opposite sides of the loom, means to reciprocate said rods simultaneously in opposite directions, means to attach said rods to the shuttles, and means to release the rods from the shuttles as the shuttles reach their central

position, said means comprising releasing rods mounted in pairs at each side of the loom, and means to reciprocate said rods alternately, whereby the upper releasing 15 rod of one pair and the lower rod of the opposite pair will be simultaneously advanced to operative position or retracted therefrom.

In testimony whereof I have hereunto 20 affixed my signature.

GEORGE CROSSLAND.
